UNITED STATES PATENT OFFICE.

JAMES E. MCWILLIAM, OF HUBBARDSTON, MASSACHUSETTS.

HORSE-BLANKET.

SPECIFICATION forming part of Letters Patent No. 683,570, dated October 1, 1901.

Application filed December 31, 1897. Renewed January 12, 1901. Serial No. 43,017. (No model.)

To all whom it may concern:

Be it known that I, JAMES E. MCWILLIAM, a citizen of the United States, residing at Hubbardston, in the county of Worcester and State 5 of Massachusetts, have invented a new and useful Improvement in Horse-Blankets, of which the following is a specification.

My invention relates to a composite horse-blanket; and the object of my invention is 10 to provide a light strong absorbent blanket which can be manufactured comparatively cheaply and which will not readily become impregnated with the odors of the stable.

To this end my invention consists of an improved fabric and the blanket made therefrom, as hereinafter described, and more particularly pointed out in the claims at the end 15 of this specification.

In the accompanying drawings, Figure 1 is 20 a plan view of a horse-blanket constructed according to my invention. Fig. 2 is a detail sectional view of the layers which are employed, and Fig. 3 is a fragmentary perspective view of a piece of the fabric.

The stable-blankets which are now used as 25 coverings for sweating or overheated horses are objectionable, as the pores of said blankets speedily become choked or clogged with dirt and grease, so that they cease to be good absorbents and are impregnated with stable-odors.

In making my improved horse-blanket I employ a central layer of rolled peat fiber, which is inclosed by facings of jute or other textile 30 material.

Peat fiber I have found to be a good absorbent, while at the same time it is light and comparatively inexpensive, and by rolling the same the central layer will be substantially 35 a felted product having considerable tensile strength.

One especial advantage in using rolled peat fiber in a horse-blanket fabric resides in the fact that the peat fiber will act as a disinfectant and will not become impregnated with stable-odors, while at the same time it is sufficiently coarse to take up a considerable quantity of moisture.

Referring to the drawings and in detail, B 40 designates a central layer of rolled peat fiber, and A and C designate facings of jute or other textile material. The inner facing C is pref-

erably considerably coarser or woven more openly than the outer facing A, so that the layer of rolled peat fiber B can more readily 55 absorb the sweat or moisture of the horse, while the outer facing A is woven sufficiently closely to retain heat, while still permitting the evaporation of moisture.

In the manufacture of my improved horse-blanket the crude peat is first pounded in any of the ordinary manners, after which it may, if desired, be associated with more or less wool-stock, and it is then passed through rollers and associated with the facings of jute, 65 the three layers being stitched or quilted together, as at 11. In some cases the central layer of peat fiber may be rolled into sheets or felted wadding first and then associated with the outer facings. The blankets may 70 then be cut from this fabric and the edges thereof bound, as at 10, and the ordinary trimmings or buckles stitched or riveted thereto in the ordinary manner.

Blankets in which I have employed wool-stock in connection with rolled peat fiber have 75 been found to be somewhat warmer than blankets which have their central layer formed from rolled peat fiber alone, and on this account I prefer to use a considerable 80 percentage of wool-stock to form the central layer; but it is obvious, however, that the wool may be omitted, if desired, or that different material may be associated with the central layer of rolled peat fiber. I do not 85 wish, therefore, to be limited to the use of peat fiber alone; but

What I do claim, and desire to secure by Letters Patent of the United States, is—

1. As an article of manufacture, a horse-blanket fabric comprising a central layer of 90 rolled peat fibers, and facings or outer layers of cloth inclosing the central layer, substantially as described.

2. As an article of manufacture, a horse-blanket, comprising a central layer of rolled peat fiber, and facings or layers of cloth, the inner facing being woven openly to provide meshes, permitting the central layer to absorb moisture, substantially as described. 95

3. As an article of manufacture, a three-ply fabric for horse-blankets comprising a central layer of rolled peat fibers and facings of textile material, the inner facing being 100

woven more openly than the outer facing, to provide meshes, permitting the central layer to directly absorb moisture, substantially as described.

5. 4. As an article of manufacture, a horse-blanket comprising a central layer of rolled peat fiber, and facings of jute, the inner facing of the blanket being woven more openly than the outer facing, and the said layers being quilted together and the edges thereof being bound, substantially as described.
5. A horse-blanket comprising a central layer B of peat and wool fiber rolled together, and facings A and C of jute, the inner fac-

ing C being woven more openly than the outer facing A to provide meshes permitting the central layer B to directly absorb moisture, the said layers being quilted together as at 11, and having their edges bound as at 10, substantially as described.

In testimony whereof I have hereunto set my hand in the presence of two subscribing witnesses.

JAMES E. McWILLIAM.
